UNITED STATES PATENT OFFICE.

THOMAS W. CHATFIELD, OF UTICA, NEW YORK.

REFRIGERATOR.

Specification of Letters Patent No. 31,782, dated March 26, 1861.

To all whom it may concern:

Be it known that I, THOMAS W. CHATFIELD, of Utica, in the county of Oneida and State of New York, have invented a new and Improved Ventilating - Refrigerator; and I do hereby declare that the following is a full and exact description thereof, reference being had to the accompanying drawing and to the letters of reference marked 10 thereon.

It consists in the arrangement of a cold air chamber A, A, A, A, around the inclosure and between the opening B, passing into the air chamber C and to A and D, 15 thereby keeping it cool in place of charcoal or other materials used by others, the ice drawer E at the side containing a cold air chamber H under the ice in the drawer E, thereby causing cold air to pass up the conducting pipes F F into the interior of 20 refrigerator, ventilating its contents on the

shelves, passing through G to top of air chamber C, passing off into the atmosphere D, making it a pure ventilating refrigerator. The air for chamber A is introduced by two 25 or more registers I, I, under the ice drawer E, making it cold, passing up A, A, A, A, mixing with the air from the inside at top register D.

This refrigerator is made of galvanized 30 or tinned iron as a non-conductor of heat.

What I claim and desire to secure by Letters Patent is—

The arrangement of the ice box E, cold air chamber H air pipes F F chamber C air 35 chamber A, A, A, A, substantially in the manner and for the purpose described.

T. W. CHATFIELD.
